F. G. HOLMES

PLATE OR SIMILAR ARTICLE

Filed March 15, 1924

Inventor:

Frank G. Holmes

Patented May 27, 1924.

Des. 64,743

UNITED STATES PATENT OFFICE.

FRANK G. HOLMES, OF TRENTON, NEW JERSEY.

DESIGN FOR A PLATE OR SIMILAR ARTICLE.

Application filed March 15, 1924. Serial No. 8,936. Term of patent 14 years.

To all whom it may concern:

Be it known that I, FRANK G. HOLMES, a citizen of the United States, residing in Trenton, in the county of Mercer and State of New Jersey, have invented a new, original, and ornamental Design for a Plate or Similar Article, of which the following is a specification, reference being had to the accompanying drawing, forming part thereof.

The figure is a plan view of a plate showing my design.

I claim:—

The ornamental design for a plate or similar article, as shown.

FRANK G. HOLMES.

Witnesses:

EDWIN T. FITZGEORGE,
WM. H. CLAYTON.
